UNITED STATES PATENT OFFICE

SAMUEL PAULL, OF NEW YORK, N. Y., ASSIGNOR TO WATER PROOF POCKET CORPORATION, A CORPORATION OF NEW YORK

BATHING-SUIT POCKET

Application filed April 13, 1927. Serial No. 183,312.

This invention relates primarily to pockets, and particularly to an air and water tight pocket which has many useful applications. It is illustrated herein in conjunction with a bathing suit as its application for such a purpose is a useful one and places the pocket under extreme conditions which best exemplify its useful characteristics.

The object of the invention is to provide 10 a pocket of a tightly sealed airproof character which may be readily applied to a garment to insure protection of articles carried therein.

A further object is to provide a resilient 15 closure so combined and correlated with other elements of structural form that there is insurance of effecting water and air tight closure. This closure also serves the purpose of slightly springing the closure members apart when they are released from permanent locked position, thus affording ease 20 in opening the pocket.

The invention herein described is similar 25 in purpose and intent to devices heretofore illustrated in my earlier Patents Nos. 1,142, 509, June 8, 1915; 1,164,010, December 14, 1915; 1,164,011, December 14, 1915, although the present invention has to do with features of refinement which are an improvement 30 over the devices of my prior patents.

Referring to the drawings:

Figure 1, illustrates the invention as applied to a bathing suit, indicating a suggested location for the pocket.

Figure 2, is a detailed view on an enlarged scale of the pocket in closed position.

Figure 3, is a top plan view showing the pocket open.

Figure 4, is a cross sectional view.

Figure 5, is a fragmentary view illustrative of the spring hinge of the closure frame.

Figure 6, is a fragmentary view showing the hooks for attachment to the fabric.

Figure 7, is a fragmentary view illustrating the attaching eyes.

Figure 8, is a view of the attached pocket partially broken away to show construction of the device in one of its forms.

Figure 9, is a vertical section through 50 Figure 8.

Figure 10, is a detailed exaggerated view illustrating the securing means of the fabric.

As indicated by reference to my prior patents, the idea of providing the waterproof pocket has already been suggested, but I have found from experimentation, that conditions arise in applying such a pocket to a bathing suit or using it for any purposes where it is subjected to immersion, which require such features as I have discovered and incorporated herein.

It is quite essential when applying such a device to bathing suits to so arrange it that it will be properly supported in the suit and may be opened and closed with facility. In 65 fact, there are decided advantages in having the purse or pocket operable with one hand of the user.

It is also highly essential that the sealing be effected in a more perfect manner than 70 heretofore and I accomplish both of these results by the manner of sealing the pocket when closed.

Referring to the drawings, numeral 1, denotes a fabric of a bathing suit which is usually knitted as a "one piece" suit having a skirt 2, with the trousers 3, and the trousers attached to the skirt and body part at the waistline as at 4. This attachment at the waistline, acts as a reenforce which really forms a belt 80 or girdle where the trousers are knit on from the body part and skirt.

My pocket may be readily applied to such a suit by forming an opening 5, therefore, in proper juxtaposition to the waistline jointure 4.

The frame A, forms the opening for my improved pocket and consists of two hinged elements 6, 7. These elements are pressed out and formed up so that there is, at their upper edges, portions 8, 9, bent at right angles, and these right angle portions extend one within the other. They provide a recess 10, within which the pocket parts are secured. There is also a resilient sealing element 11, which completely fills and hermetically seals the frame parts and pockets within the recess 10.

The body of the pocket 12 consists of a water tight material which may be fabric,

fabric and rubber or interlaminated materials of fabric and rubber.

The inner side of the frame has attaching hooks 18, shown in Figure 6, or equivalent split rivets illustrated in Figure 10, which are passed through the fabric of the upper end of the pocket and bent down flat, against the walls of the frame to secure the fabric thereto.

10 The fabric, of course, may be cemented to the walls of the frame and the inner face of the fabric, after the hooks have been fastened therethrough, is preferably coated with cement to secure tight joints about the hook members 13. This cementing is not absolutely imperative, but adds a safeguarding feature.

A perfectly tight closure is effected by an annular and continuous loop of material 14.

20 I have found one solution of the problem of tightly closing the frame by utilizing a resilient material for this annular strip 14, which consists of a spongy form of rubber 15, having all its outer surface covered with 25 a surfacing of tight rubber as distinguished from sponge rubber. This gives smooth meeting faces over the resilient strip 14, and permits of a perfect cementation of the faces 16, thereof, to the fabric of the pocket and to 30 the metal frame.

When this strip 14, is cemented over the fabric and the retaining hooks 13, there is a perfect closure between the elements.

At the same time, the spongy character 35 of the rubber permits a great degree of compression of the annular element 14, and this, in itself, insures disposition of the strip over the meeting edges of the frame and appurtenant parts, which makes a perfect seal.

40 In addition to the sealing of the top of the pocket, at the frame, the spongy sealing element, under considerable compression, serves as a spring for throwing the two jaws of the frame open whenever the clasp 17, releases 45 them. I find a further advantage in this smooth surfaced sponge rubber sealing element, in that the sponge rubber, of course, offers almost innumerable air pockets which, under compression, serve to give an entirely 50 tight hermetic seal and also activates the rubber so that it does not become hardened and deadened as does ordinary soft vulcanized rubber.

It also permits comparatively easy closing 55 of the jaws of the frame and yet is resilient enough to throw them open when they are released by raising the clasp 17.

This clasp is of ordinary type pivoted as at 18, to one of the frame members and having dependent side parts 19, 20, which form a firm clamp over the interengaged jaws of the frame.

Any suitable and ornamental finger piece 60 21, is attached to one of the jaws to hold the 65 jaws open.

The lower end of the two frame elements are pivoted as at 22, and are cut, one within the other, having substantial concentric terminal parts 23, 24.

The part 24, extends upward against the 70 frame element 7, and thus serves in conjunction with a pivot 22, as a spring hinge for normally tending to close the jaws of the frame.

Inasmuch as the annular resilient member 75 14, is made in a single piece, as heretofore stated, is completely covers joints and pivot openings about the pivot 22, and the parts 23, 24.

It is apparent that even though the 80 resilient member was slightly displaced with reference to the pivot, it would still form a water tight closure, as the frame parts would compress it entirely about the frame.

I provide, therefore, not only the interengaging frame jaws with the back or body of the pocket 12, tightly secured therein, but I provide what is, in effect, a resilient pair of jaws within the two hinged jaws of the frame.

90 The two are so correlated that there must always be a tight closure.

I have found when utilizing a solid rubber under the pressures which are exerted when the pocket jaws are closed, that they soon 95 become deadened, hardened and permit leakage. However, with the composite spongy and closed surface element, such a result does not occur.

100 In applying the device to a bathing suit, I provide eyes 25, 26, which may be stitched or sewed to the waistline belt of the garment while the purse or pocket projects through the opening 5, of the garment.

I also attach the lower portion of the 105 frame to the garment through eyes 27, similar to those above described.

As an additional security which is permitted by this arrangement, I cement one side of the pocket to the garment above the 110 opening 5, and cement the opposite side thereof to the garment to the inside and below the opening 5.

This, in conjunction with the attachment to the waist-band, prevents sagging and 115 holds the pocket in proper position at all times.

A pocket of considerable depth may be utilized and all that shows is the portion of the frame and pocket which projects above 120 the opening 5.

To insure maintenance and closure of the clasp 17, I displace the metal of the frame as at 17a, and the metal of the clasp as at 17b, so that there is a snap action for holding the 125 clasp in locked position.

In Figures 8 to 10, of the drawings, I have illustrated, with more elaboration, the preferred form of my invention.

130 All of the elements of this preferred form

are substantially the same as heretofore described, except that I now give the preferred manner of waterproofing the bag portion of the pocket. I provide an outer casing of material, 50, rubberized on both sides and which is cemented to the skirt 2, as at 51, with the opposite side thereof cemented at the rear as at 52. This use of rubberized outer casing permits this cementation.

10 There is an inside fabric 53, which is rubberized on the outside surface 54, and not rubberized on the inner surface 55. This gives a feeling of warmth and fabric to the interior of the pocket.

15 Between the outer rubberized member 50, and the inner rubberized member 53, I place a full rubber element 56. This arrangement, when the three bags are tightly closed and cemented at the top insures perfect insulation between the inside and outside of the bag, thereby preventing condensation and sweating.

20 The outer element acts as a securing means and protector for the more delicate rubber bag 56, from the outside and the inner partially coated fabric 55, protects it from the inside. Of course, each of the pocket elements is substantially air and water tight when they are sealed together at their upper 25 edges and therefore, there are air pockets formed between the several bag elements.

At the same time, there are sealed air gaps between the inner rubber 56, and the outside and also between the inside 55, and the rubber 56.

30 It is of course, apparent that a plurality of bags, whether there be two or three, will effect much the same general condition of giving an air gap insulation between the inside and outside of the pocket.

35 In securing the bag elements to the frame, I prefer to employ a split pin 57, which passes through the frame part 58, and is turned over as at 59, to clinch the fabric elements of the bag or pocket.

40 In manufacture, I use a softer swedging metal for these pins than is employed in the frames and swedge the pins through the frame so that there is no leakage. These rivets or pins, at their heads, give an ornamental embellishment to the frame. They may be of a different color from the frame and the heads may be embellished to give the appearance of jewelry.

45 Obviously, the details of form and shape may be modified to an appropriate extent without departing from the spirit and intent of the invention and pockets of various size and shape may be used to suit the exigency 50 of any particular requirement so long as the advantageous features heretofore described are retained.

55 What I claim as my invention and desire to secure by letters patent is:

60 1. A pocket of the character described,

comprising an outer rubberized pocket, a full rubber pocket within and a partially rubberized pocket forming the inner lining whereby two insulating chambers are provided between the outside and the inside of the pocket.

65 2. A pocket of the character described, having two jaw members pivoted one to the other, one of said jaw members having an integral extended portion providing a spring for engaging opposed elements and normally tending to close the jaws, a continuous piece of highly resilient packing conforming to the jaws and filling the space between said jaws, said packing offering a resistance to the closure of the jaws and a hermetically sealed fabric pocket, hermetically sealed by the closure of the jaws and its highly resilient packing.

70 3. A pocket of the character described, having a closure consisting of two pivoted jaws, said jaws having interengaging flanges providing a chamber between the jaws, a fabric bag secured to the jaws within the chamber and a single piece highly resilient sponge rubber cushion with a tight rubber surfacing therefor, said cushion being substantially coextensive with the chamber and compressible therein to form a hermetic seal for the jaws and attached bag.

75 4. A pocket of the character described having pivoted jaws flanged and spaced to provide a chamber between the jaws, a bag secured to the jaws within the chamber and a single piece highly resilient cushion substantially coextensive with the chamber and consisting of a sponge rubber, surfaced with tight rubber.

80 5. In a pocket of the character described, a frame having interengaging pivoted jaws, a fabric pocket having a plurality of pocket elements, sharpened metallic elements between the frame and said pocket elements extending through the frame members and through the pocket elements and compressible into the elements to bind said elements to the frame in fixed relation and a single piece of highly resilient packing of spongy consistency having a maximum of compressibility secured and cemented within the jaws and to the fabric and forming an hermetic seal with reference to the jaws, pivots thereof and the pocket elements.
